UNITED STATES PATENT OFFICE.

MORRIS SCHOENFELD, OF ZURICH, SWITZERLAND.

SPOOL.

Application filed January 22, 1926. Serial No. 83,166.

My invention relates to spools and their holders, and more particularly to spools on which yarn or thread is to be wound for undergoing various processes. In the handling 5 of rayon or artificial silk, it is common to wind the thread upon spools comprising perforated or foraminous cylinders and to subject the thread, while retained on the spool, to various steps or processes such as bleaching, dyeing, and the like; and the present device is intended to provide a spool for facilitating the carrying out of these various steps or processes. The present device may be of perforated or foraminous construction to allow 15 the chemicals, water, air etc. to pass freely through the walls of the spool. It includes not only the stationary walls of the spool, but certain other elements which temporarily increase the perimeter of the spool 20 while the thread or yarn is being wound thereon, and which may be retracted after the thread or yarn has been wound, in order to allow the body of thread or yarn to slacken in order to loosen it to permit the various 25 chemicals or water to pass between the various turns of the thread or yarn in order to effectively treat all portions thereof, notwithstanding the fact that a considerable quantity of the thread or yarn is wound in a compact 30 body. These retracting members are adapted to be held in extended position while the thread or yarn is being wound upon the spool, so that it may be wound with a slight tension 35 in regular layers to avoid twisting and snarling of the turns of thread; and after a sufficient quantity of thread or yarn has been wound upon the spool the retracting members may move inwardly in order to release the tension upon the body of thread or yarn and 40 allow it to loosen while being subjected to various treatments, in order that the liquids may affect the entire surface of the different turns of thread or yarn and in order that the total body of thread or yarn may temporarily 45 shrink if the process causes this result. After the thread has been subjected to the treatment in liquid baths, and in some cases to hot air for drying, the retracting members may be again forced outwardly to tighten the body of 50 thread and they may be held in this position while the thread is being unwound from the spool in order that the same will not become tangled during the rewinding operation. While the thread or yarn is on the spool, various 55 fluids, heat etc. may be forced to pass through all portions of the body of thread or

yarn. I also provide simple means for holding the retracted members in their outer position and for simultaneously revolving the spool either to wind the thread thereon, or to 60 unwind the thread therefrom.

In the drawings forming part of this application,

Figure 1 is a longitudinal sectional view of one form of spool embodying my invention 65 and showing one of the chuck members withdrawn from the spool,

Figure 2 is a cross sectional view of the same spool and showing the retracted members in their inner position, the outer position 70 being indicated by dotted lines.

Fig. 2' is a fragmentary sectional view corresponding with that shown in Fig. 2 but showing the retracting members in their fully retracted position. 75

Figure 3 is a longitudinal sectional view of another form of my invention and showing the spool chucks in position for revolving the spool,

Figure 4 is a cross sectional view showing 80 another form of my invention,

Figure 5 is a perspective view of one of the retracting members employed in the form of the invention shown in Figure 4,

Figure 6 is a similar view of a corrugated 85 form of retracting member which may be used in place of the members shown in Figure 4,

Fig. 6' is a view corresponding to Fig. 1 but showing the structure of Fig. 6. 90

Figure 7 is a partial longitudinal sectional view showing another form of my invention,

Figure 8 is a cross section of another form of the invention in which the retracting members may be moved in and out while the spool 95 is being revolved,

Figure 9 is a partial longitudinal sectional view of the form shown in Figure 8, and

Figure 10 is a cross sectional view showing 100 still another form of the invention in which the retracting members may lie flush with the periphery of the spool.

Referring first to the form of the invention shown in Figures 1 and 2, the spool consists of a cylindrical body 1 which is made foraminous by the provision of a series of apertures 2 arranged at close intervals throughout the wall of the cylinder 1. The ends of this cylinder are flared outwardly at 3 and the edges are rolled to provide a rim 4. In this form of 105 the invention the retracting members 5 are adapted to move radially of the cylinder in 110

slots 6 extending lengthwise of the cylinder and they are adapted to be prevented from falling within the cylinder by means of lips 7 arranged at each end of the retracting members, these lips being adapted to rest against the outer surface of the flared portions 3 of the spool when the retracting members are in their inner position, as shown in Figure 1. To prevent the retracting members from falling out or away from the cylinder, I have provided lateral flanges 8 which lie within the cylinder and are wider than the slots 6 so that the retracting members will be limited in their outward movement by the engagement 15 of the flanges 8 with the perimeter of the cylinder 1. Each retracting member includes a vertical wall 9 which moves radially of the cylinder within the slot 6. At the right of Figure 1 I have shown a chuck member for 20 extending the retracting members and for holding one end of the spool while it is being revolved, and it will be understood that a similar member will be provided for the opposite end of the spool the same as in Figure 3. 25 This chuck member consists of a head 10 which may be carried on a suitable shaft and the forward end is frustro conical shape as shown at 11 in order to be inserted into the end of the spool. The smaller end of this frustro conical member is of slightly less diameter than the circle formed by the several flanges 8, when the retracting members are in their inner positions. When this chuck member is inserted into the end of the spool and a 30 similar member is inserted into the opposite end of the spool, the frustro conical portions will engage the several flanges 8 and force the retracting members outwardly. This will project the latter members approximately to the dotted line position shown in Figure 2, and while the parts are in this position the chucks 10 together with the spool, may be revolved, and the thread or yarn will be wound 35 on the projecting edges of the retracting members. These members will increase the peripheral dimension of the spool during the winding operation so that the yarn or thread may be wound upon these members with sufficient tension to lay the thread or yarn in regular layers upon the spool. After the thread 40 or yarn has been wound upon the spool the chucks 10 are withdrawn endwise, whereupon the retracting members may move radially inwardly in relation to the spool and this will permit the body of thread or yarn to slacken and thus permit the several layers to loosen or 45 separate sufficiently to allow the entire body of thread or yarn to be treated throughout all portions. The spool with the body of thread 50 or yarn may then be subjected to various baths for bleaching or dyeing and to hot air treatment, the apertures in the spool permitting the various fluids to pass through in order that all portions of the thread or yarn 55 may be thoroughly treated. After the thread

or yarn has been passed through the different processes, the chucks 10 may be again inserted endwise into the spool in order to force the retractile members outwardly and place the body of thread or yarn again under tension. 70 In this condition the spool may be revolved to unwind and remove the thread or yarn.

In Figure 3 I have shown a modified construction wherein the retractile members 11^a have an ear 12 at one end pivoted by means of a pin 13 to the spool at one end, and the opposite end of the retractile member has a projection 14 for engaging against the outer surface of one end of the spool to prevent this end from dropping entirely into the spool. 75 The retractile member is tapered lengthwise as shown in Figure 3 in order that when its free end is swung outwardly by the chuck 10 the outer surface of the retractile member will remain parallel with the axis of the spool. 80 Alternate retractile members are shown with their pivots in alternate position, that is to say, while the retractile member 11^a is shown pivoted at the left hand end of the spool in Figure 3, the retractile member 15 is shown pivoted at 16 to the right hand end of the spool. In this way alternate retractile members may be pivoted at opposite ends of the spool so that the free ends of one set of retractile members will be engaged by the 85 right hand chuck while the corresponding ends of the alternate retractile members will be engaged by the left hand chuck 10. This device is used in the same manner as the form 90 shown in Figures 1 and 2.

In Figures 4 and 5 I have shown another form of the invention in which the spool proper remains the same but the retractile member, in addition to the vertical wall 17 radially disposed in relation to the spool, 105 and the inner flange 18 for limiting the outward movement of the retractile member, has an arcuate plate 19 lying outside of the spool and on which the thread or yarn is adapted to be wound. These plates 19 provide larger surfaces for engagement of the thread or yarn and I prefer to provide these plates with a series of apertures 20 throughout their surfaces in order to permit fluids to 110 pass through these plates to reach all portions 115 of the yarn or thread. In this form the inner flanges 18 limit the outward radial movement of the retractile members, and the plates 19 limit the inner radial movement. The same type of chucks as shown in Figures 120 1 to 3 may be used for holding and rotating this type of spool.

In Figure 6 I have shown retractile members adapted to be used in the same manner as in Figure 4, but in this form the outer plate 21 is provided with a longitudinally corrugated plate 22 also provided with apertures 23. The object of this form is to provide a member which will engage the yarn at 125 many points and at the same time allow the 130

fluid to reach all portions of the yarn or thread by flowing along the grooves of the corrugated plate and through the apertures 23.

In Figure 10 the construction is modified 5 to the extent that the cylinder wall is provided with a number of indentations 24 extending lengthwise thereof in which the outer plates 19 of the retractile members may be received so that the outer surfaces of these 10 plates lie flush with the periphery of the cylinder when the retractile members are in their inner position.

In Figure 7 the retractile members are shown as comprising rods 25 extending 15 lengthwise of the spool and the ends of these rods are bent downwardly at right angles and thence turned inwardly at 26 within the wall of the spool. These bent ends of the rods prevent the retractile members from moving 20 out of the spool and the retractile members may move in and out a distance corresponding with the space between the rod portion 25 and the surface of the spool as shown in Figure 7. The same type of chuck may be 25 used in connection with this form of spool as is shown in Figures 1 to 3.

In Figures 8 and 9 I have shown another form of the invention wherein the retractile members may be moved in and out while 30 the spool is being revolved, in order to allow the fluid to pass between the thread or yarn and the surface of the spool, and in fact through all portions of the thread or yarn. In this form of the invention the retractile 35 members may consist of radial plates 27 moving in longitudinal apertures 28 in the wall of the spool; and the lips 29 on the ends of the retractile members may serve to hold them from falling inwardly in the spool the 40 same as in Figure 1. In this case there is a polygonal arbor 30 extending through the spool for supporting the same. This member, which is shown as square in cross section in the drawing, may be revolved, and when 45 in the position shown in Figure 8 the member 30 carries one of the retractile members on its top surface and the weight of the spool and thread forces the retractile member radially outwardly in relation to the spool so that the thread or yarn at this point is lifted 50 up from the surface of the spool as shown at 31. As the member 30 turns it will cause the spool to slowly revolve and as the next flat surface of this member comes into the upper 55 position it will engage the next succeeding retractile member and lift it, at the same time permitting the first one to drop back into retracted position. In this manner the spool is revolved by the member 30 and the retractile 60 members are one at a time moved in and out to work the thread or yarn and allow fluid to pass through all portions.

Having described my invention, what I claim is:

1. A spool on which thread or yarn may be

wound and while on the spool subjected to dyeing or other treatment while in a slack condition on the spool, comprising a cylindrical body, a plurality of retractile members, adapted to be extended from said body to receive the thread or yarn thereon and to retract to permit the wound thread or yarn to slacken. 70

2. A spool on which thread or yarn may be wound and while on the spool subjected to 75 dyeing or other treatment while in a slack condition on the spool, comprising a cylindrical body, and retractile members associated therewith, said body having longitudinal slots in which said retractile members 80 are adapted to move whereby they may be extended from said body to receive the yarn or thread thereon, said retractile members being adapted to move inwardly in relation to the periphery of said body, to permit the 85 thread or yarn to slacken.

3. A spool on which thread or yarn may be wound and while on the spool subjected to 90 dyeing or other treatment while in a slack condition on the spool, comprising a cylindrical body having longitudinal slots, a plurality of retractile members movable radially of said body in said slots and adapted to be extended from said body to receive the thread or yarn thereon, and to retract to permit the 95 wound thread or yarn to slacken, and means for limiting the radial movement of said retractile members.

4. A spool on which thread or yarn may be 100 wound and while on the spool subjected to dyeing or other treatment while in a slack condition on the spool, comprising a foraminous, cylindrical body having longitudinal slots and a plurality of retractile members movable in said slots radially of said body, 105 and adapted to be extended from said body to receive the thread or yarn thereon and to retract to permit the wound thread or yarn to slacken.

5. A spool on which thread or yarn may be 110 wound and while on the spool subjected to dyeing or other treatment while in a slack condition on the spool, comprising a cylindrical body having longitudinal slots and a plurality of retractile members having vertical walls movable in said slots radially of 115 said body and having lateral extensions within said body to limit the outward movement of said retractile members, said retractile members being adapted to be extended from 120 said body to receive the thread or yarn thereon and to retract to permit the wound thread or yarn to slacken.

6. A spool on which thread or yarn may be 125 wound and while on the spool subjected to dyeing or other treatment while in a slack condition on the spool, comprising a cylindrical body, a plurality of retractile members adapted to be extended from said body to receive the thread or yarn thereon and to 130

retract to permit the wound thread or yarn to slacken, and a chuck insertable into said body to hold said retractile members in extended position for the winding or unwinding of the thread or yarn.

7. A spool on which thread or yarn may be wound and while on the spool subjected to dyeing or other treatment while in a slack condition on the spool, comprising a cylindrical body, a plurality of retractile members adapted to be extended from said body to receive the thread or yarn thereon and to retract to permit the wound thread or yarn to slacken, and a chuck having a frustro conical portion adapted to engage said retractile members and to hold them in extended position while the spool is being revolved.

8. A spool on which thread or yarn may be wound and while on the spool subjected to dyeing or other treatment while in a slack condition on the spool, comprising a cylindrical body having longitudinal slots, retractile members having radially arranged walls movable in said slots, said retractile members having means engaging the outer surface of said body to limit the movement of said retractile members in one direction, said retractile members having lateral extensions on their inner edges for limiting the outward movement of said retractile members.

9. A spool on which thread or yarn may be wound and while on the spool subjected to dyeing or other treatment while in a slack condition on the spool, comprising a cylindrical body having longitudinal slots, retractile members having radial walls movable in said slots and having laterally extending arcuate walls externally of said body, said retractile members being adapted to be extended to receive the thread or yarn on said arcuate walls and to retract to permit the wound thread or yarn to slacken.

10. A spool on which thread or yarn may be wound and while on the spool subjected to dyeing or other treatment while in a slack condition on the spool, comprising a cylindrical body having longitudinal slots, retractile members having radial walls movable in said slots, and having foraminous, arcuate walls externally of said body, said retractile members being adapted to be extended to receive the thread or yarn on said arcuate walls and to retract to permit the wound thread or yarn to slacken.

11. A spool on which thread or yarn may be wound and while on the spool subjected to dyeing or other treatment while in a slack condition on the spool, comprising a cylindrical body having longitudinal slots, retractile members having radial walls movable in said slots and having arcuate, laterally extending plates outside of said body, said plates having longitudinal corrugations, said retractile members being adapted to be ex-

tended from said body to receive the thread or yarn thereon and to retract to permit the wound thread or yarn to slacken.

12. A spool on which thread or yarn may be wound and while on the spool subjected to dyeing or other treatment while in a slack condition on the spool comprising a hollow cylindrical body whose external periphery constitutes a bearing surface, and having between its ends longitudinally extending slots that open from the interior to the outside, and a member situated in each of said slots free to move radially outward and inward with portions reaching to the interior of the body and exposed for engagement by means to project said members radially outward, the outer portions of said members being bearing surfaces the outward movement of said members being to a point which carries such bearing surfaces beyond the periphery of the cylindrical body and the inward movement permitting the thread or yarn to slacken.

13. A spool on which thread or yarn may be wound and while on the spool subjected to dyeing or other treatment while in a slack condition on the spool, comprising a hollow cylindrical body whose external periphery constitutes a bearing surface, and having between its ends longitudinally extending slots that open from the interior to the outside, and a member situated in each of said slots free to move radially outward and inward with portions reaching to the interior of the body and exposed for engagement by means to project said members radially outward, the outer portions of said members being bearing surfaces, the outward movement of said members being to a point which carries such bearing surfaces beyond the periphery of the cylindrical body and the inward movement permitting the thread or yarn to slacken, said members having portions to engage the inner and outer peripheries of the cylindrical body to limit radial movement thereof in both directions.

14. A spool on which thread or yarn may be wound, and while on the spool subjected to dyeing or other treatment while in a slack condition on the spool, comprising a cylindrical body having longitudinal slots, radially movable members having portions that lie within the respective slots and reaching within the cylindrical body, said members moving radially of said body within said slots to reach beyond the body periphery, and a chuck insertable into the end of said body and adapted to move said members outward to project them beyond the body periphery.

Signed at the city, county and State of New York, the 8th day of December, 1925.

MORRIS SCHOENFELD.
